UNITED STATES PATENT OFFICE

CHARLES A. CRARY, OF WYOMING, OHIO

DESIGN FOR A CAKE OF SOAP

Application filed June 18, 1930. Serial No. 36,095. Term of patent 14 years.

To all whom it may concern:

Be it known that I, CHARLES A. CRARY, a citizen of the United States, residing at Wyoming, in the county of Hamilton and State of Ohio, have invented a new, original, and ornamental Design for a Cake of Soap, of which the following is a specification, reference being had to the accompanying drawing, forming part thereof.

I claim:

The ornamental design for a cake of soap, as shown.

CHARLES A. CRARY.
